PRINTING PRESS

John S. Rogowski, Chicago, Ill., assignor of one-third to Saul Kahn and one-third to Helen Kahn, both of Chicago, Ill.

Application December 18, 1939, Serial No. 309,882

5 Claims. (Cl. 101—216)

This invention relates to the art of printing, and while it is of general application, it is more particularly concerned with offset printing, the principal object being the provision of means for preventing slippage between the plate and a tractionally interdriven form roller adapted to transfer ink onto the plate.

Viewed from another aspect, it is a principal object of the invention to provide, in combination with a plate cylinder and inking roller adapted to be frictionally driven with the plate on the cylinder, a plate etched or otherwise formed so as to have a recessed portion surrounded by a border, with the copy disposed in the recessed portion and the ink-receiving surfaces of the copy situated at the same level or in the same plane with the surfaces of the border portion, particularly those parts thereof which extend in a direction circumferentially of the plate cylinder, there being tractional rolling engagement between certain border portions and corresponding parts of the next inking roller, and means for preventing transfer of ink to the traction surfaces.

A further object is the combination with a plate cylinder, a form roller adapted to be frictionally driven against a plate on said cylinder, and a series of at least two other peripherally driven rollers for transferring ink onto the inking roller, of means for preventing slippage between the inking roller and plate, which comprises the provision of a plate having friction drive surface portions extending in a direction circumferentially of the plate cylinder and flanking a recessed portion in which the copy is etched, the ink receiving surfaces of said copy being situated at the same level as said friction drive surfaces, and that one of the ink transferring rollers which bears against said inking roller having its peripheral contact surface portions of shorter length than said inking roller whereby to leave uninked areas adjacent the axial ends of the latter of an extent adequate to prevent transfer of any ink to the friction drive surface of the plate.

Viewed from still another aspect, it is an object of the invention to provide, in combination with a plate cylinder, a plate having friction drive surfaces formed integrally at its ends corresponding to the axial ends of the plate cylinder and extending in a direction circumferentially of the latter, and an inking roller bearing against said plate and said friction drive surfaces, and another ink transferring roller bearing against said inking roller and having reduced peripheral surface portions at its axial ends, said surface portions being of an extent in an axial direction

at least equal to the width in the same direction of said friction drive surface on the plate, whereby to prevent the transfer of ink onto said friction drive surfaces and obviate slippage.

Other objects, advantages and novel aspects of the invention reside in certain details of construction as well as the cooperative relationship of the embodiment described hereinafter in view of the annexed drawing, in which:

10 Fig. 1 is a perspective view of one form of roller arrangement in an offset press and in which arrangement the invention has been incorporated;

Fig. 2 is a diagrammatic illustration of the roller arrangement of Fig. 1;

Fig. 3 is a plan view of the novel plate;

Fig. 4 is a cross section through the plate along line 4—4;

Fig. 5 is an enlarged fragmentary detail of the rolling engagement between the ends of the riding and form rollers.

For purposes of illustration, the roller assembly employed in offset printing has been shown in Fig. 1, which arrangement includes an inking drum or roller 10 adapted to receive ink from a source of supply (not shown) and rotated by the power drive means of the press in the customary manner, preferably through a connection with the plate cylinder. This inking drum, in addition to its rotary movement is customarily oscillated along its axis by means of a cam drive indicated at 11, the purpose being to assure a uniform and positive distribution of the ink to the other rollers of the series.

In accordance with the usual practice in offset printing, ink is transferred through a series of rollers onto a zinc plate 12 which is etched with the copy 12a. The plate is placed on a plate cylinder 13 and clamped in position as at 13a (Fig. 2), the cylinder being rotated to effect transfer of ink from the system of rollers onto the copy, which ink is in turn transferred onto the surface of an offset roller 14 in conformity with the copy 12a and indicated at 12b on the offset roller.

Means for transferring ink from a source of supply onto the zinc or plate, includes the provision of a system of serially arranged rollers including the inking drum 10, an intermediate transferring roller 15, and another intermediate transferring roller 16 known as a rider, which in turn bears against the actual inking roller 17 known as a form roller. As a result of the serial peripheral rolling engagement between the rollers of the system, it will be evident that ink will be transferred from the drum 10 onto the copy

12a on the plate, when the several rollers are jointly driven.

Referring to Fig. 2, a driving arrangement for certain of the rollers, customarily employed in this type of press, includes the provision of a master driving gear diagrammatically indicated at 20 (not seen in the other figures) and which meshes with a driving gear on the inking drum 10, a driving gear on the rider 16, and also a driving gear on the plate cylinder 13. In the diagram of Fig. 2, the roller assembly has been duplicated in accordance with actual practice, and it will be observed that of the series of rollers, the intermediate roller 15 and the form roller 17 have no positive driving connection with the master gear 20, but rely upon frictional engagement with the riding roller 16, the inking drum, and the plate cylinder for their driving power.

It is highly important to assure proper distribution of the ink on the copy or zinc etching, and this is best accomplished by having the form roller 17 frictionally driven with the plate cylinder and more particularly with the surface of the plate thereon; however, in order to employ such a friction drive, it is also essential that all slippage between the form roller 17 and the plate be wholly eliminated.

In accordance with prior practice, it was customary to spray with water or moisten portions of the frictionally interdriven roller members from which it was desired to exclude ink, such inks of necessity being water-insoluble, particles of water lodging in the grain or crevices in the plate substantially below the printing surface thereof so as not to interfere with the frictional drive. However, a great deal of offset printing must be done with water-soluble inks, and it is therefore impossible to resort to such a spraying or moistening expediency, since the same would be ineffective and moreover would introduce the serious danger of running of colors off margin or register.

The present invention therefore has as its object the provision of a relatively simple and inexpensive means for preventing such slippage regardless of the nature of the ink used, said means including the provision of a plate 12 (Fig. 3) which has integrally formed friction drive surfaces, the plate being recessed as at 18 in the regions surrounding the copy 12a and in a manner which will leave a substantial border 19 with frictional drive surfaces 19a at opposite sides of the plate and extending in a direction of the circumference of the plate cylinder.

The plate may be made in the foregoing form either by routing, gouging or etching out the surplus material around the copy within the border portions. It is important to observe in Fig. 4, particularly, that the depth of the border 19a and the copy 12a is substantially the same, so that the ink receiving surface portions of the copy 12a, in other terms, lie at the same level or in the same plane as the friction surface portions of the border parts 19a, the reason for which will appear hereinafter.

The invention is completed by providing on the riding roller 16 peripherally reduced surface portions 16a at the ends thereof, these surface portions extending in an axial direction at least a distance equal to the width, in the same direction, of the frictional drive surfaces 19a. In consequence of this arrangement, it will be evident that no ink will be transferred to the correspondingly positioned end portions 17a on the form roller, the latter surface portions being those which are

frictionally engaged with the surface portions 19a on the plate so that ink will be excluded from the latter surface portions with a consequent minimizing of the danger of slippage, particularly as it might result from the driving engagement of inked or moistened surfaces.

It should be pointed out that the riding roller 16 is usually oscillated in the same manner as the ink drum 10, and therefore means is provided for preventing the transfer of ink onto the traction surface 17a as a result of such oscillation, this means comprising the provision on the form roller 17 and between the traction surfaces 17a and the intervening peripheral portions of the roller, of peripherally reduced portions 17b (Fig. 5 particularly) in the nature of grooves or channels of shorter radius than the adjoining peripheral surface portions of a width measured in an axial direction adequate to permit axial displacement or oscillation of the roller 16 so that the main peripheral margin thereof at the juncture with the reduced portions 16a will not be shifted onto the traction surfaces 17a.

An added advantage of this latter arrangement resides in the fact that even though the riding roller 16 may be disconnected from its oscillating means, as is sometimes desirable in offset printing, there will be no danger of ink creeping onto any part of the traction surface 17a of the form roller should the press be continuously driven on a big run.

Rollers 16-17 and the plate cylinder 13 constitute a plurality of peripherally rolling drums or members arranged in a series, the rider being regarded as the first roller and being one of the outer rollers with respect to an intermediate roller 15, and the plate cylinder 13 constituting a third outer roller on the opposite side of the intermediate roller in the series.

In the application and operation of the present invention as applied to the type of press described, the new form of plate shown, for example in Fig. 3, is laid onto the plate cylinder 13 and attached as at 13a in the customary manner. Assuming the riding roller 16 to be provided with the reduced end portions heretofore described, and the oscillatory drive for this roller to have been disconnected, it will be apparent that upon rotation of the system of rollers and the cylinder, ink will be transferred from the drum 10 to the intermediate roller 15 and thence to all but the reduced or receded surface portions 16a of the riding roller, with a consequent transfer of the ink to the corresponding surface portions of the form roller 17, there being an absence of ink on the end portion 17a of the form roller and a consequent absence of ink from the frictional or tractional drive surfaces 19a on the circumferentially extending border portions of the etched plate. A very large number of impressions can be run without any likelihood of ink working from the positively inked portions of the form roller onto the uninked portions 17a thereof, owing to the reduced parts 16a, 17b.

The various advantages and objects of the invention may be accomplished by modifications of the particular embodiment specifically described herein, and it is intended that the appended claims shall include all equivalent arrangements fairly coming within their call.

Having thus described my invention, what I claim as new and desire to protect by Letters Patent is:

1. In a printing press or the like including an ink receiving cylinder having frictional driving

engagement with a form roller, a riding roller peripherally contacting the form roller and an intermediate roller which in turn peripherally contacts an inking drum, said drum, rollers, and ink receiving cylinder being of substantially the same length and said inking drum being supplied with ink for transfer through the intervening rollers onto said ink receiving cylinder, means for preventing slippage between the frictionally driven form roller and cylinder which comprises the provision of a riding roller of shorter length than said intermediate and form rollers whereby to prevent transfer of ink to those end portions of the form roller disposed beyond the ends of the shorter riding roller with a consequent absence of ink at the corresponding ends of said ink receiving cylinder to provide uninked peripheral areas on the form roller and ink receiving cylinder to improve the frictional contact between said uninked surfaces.

2. In a device of the class described including a cylinder adapted to receive ink on its periphery, and a series of at least three ink transferring rollers including a first, an intermediate, and an outer roller, said outer roller being supplied with ink for transfer to the other rollers, said first roller being driven through frictional contact with said cylinder, said intermediate roller having receded peripheral surface portions of uniformly lesser radius than other surface portions thereof and which are out of contact with the cylinder and intermediate roller whereby no ink will be taken from the latter on said receded portions and no ink will be transferred to the surface portions of said outer roller which are opposite the receded surface portions, with a resulting absence of ink on corresponding portions of said cylinder whereby uninked peripheral driving surfaces are provided on said outer roller and cylinder to reduce slippage between the same.

3. In a device of the class described, a system of inking and inked rollers including at least four rollers arranged in serial peripheral contact for rotation together, at least the last two rollers of the series being frictionally driven, one from another, the outermost roller of the remaining two of the series being adapted to receive ink from a supply source, means for reducing slippage between the frictionally driven rollers, comprising the provision of uniformly inset peripheral surface portions on the roller engaging said outermost roller and which are out of contact with the latter so as to receive no ink therefrom and which inset portions are thereby incapable of transferring ink onto correspondingly positioned portions of said last two frictionally driven rollers.

55

4. In a device of the class described, the combination of a plurality of at least three rollers arranged for peripheral rolling engagement in series, a first roller of said series being adapted to have its peripheral surface portions supplied with ink, said ink being transferred to the next adjacent or second roller of the series in rolling action, the ink in turn being transferred from said second roller to the third roller of the series, said second and third rollers being arranged for tractional driving engagement at axially spaced points, and means for preventing the transfer of ink onto the traction portions of said rollers, said means comprising the provision of axially spaced peripherally reduced portions on said first roller which are of shorter radius than the surface portions intervening therebetween and in consequence out of contacting engagement with the correspondingly opposite surface portions on the next adjacent or second roller whereby no ink will be transferred to said correspondingly adjacent surface portions, the latter being tractionally engaged with corresponding surface portions on the third roller, said second roller being provided with peripherally reduced surface portions positioned substantially opposite the juncture of said peripherally reduced portions with said intervening portion on the first roller, whereby to prevent the creepage of ink onto the traction surface of said second roller from the intervening surface portions on the latter and also to permit axial oscillation of said first roller an amount depending on the extent in an axial direction of the reduced portions on said first roller.
5. In a series of at least three peripherally rolling inked and inking rollers, at least two of which are in tractional driving engagement, means for preventing the transfer of ink to the traction surfaces which comprises the provision of peripherally reduced inking surface portions on a first one of said rollers whereby ink is prevented from passing onto correspondingly opposite portions of the second and third rollers, said second roller having circumferentially grooved portions disposed approximately opposite the juncture of the reduced and normal surface portions of the first roller to prevent creepage of ink onto the normally uninked portion of the second roller and also to permit axial displacement of said second roller distances depending on the width of said grooved portions, and means for inking the normal unreduced surface portions of the first roller.

JOHN S. ROGOWSKI.
